UNITED STATES PATENT OFFICE.

DANIEL WATSON, OF ARGENTINE, KANSAS.

CAR-ROOF.

SPECIFICATION forming part of Letters Patent No. 639,322, dated December 19, 1899.

Application filed May 22, 1899. Serial No. 717,747. (No model.)

To all whom it may concern:

Be it known that I, DANIEL WATSON, a citizen of the United States, residing at Argentine, in the county of Wyandotte and State of Kansas, have invented certain new and useful Improvements in Car-Roofs, of which the following is a specification.

My invention relates to car-roofs; and my object is to produce a car-roof of that type which automatically accommodates itself to the movements of the parts of the car structure, and thereby is preserved intact, and obviates all chance of leakage through the roof due to the formation of cracks or the opening of seams occasioned by the twisting or rocking of the roof under the various strains to which it is subjected in actual use, embodying the features of simplicity, strength, and durability with cheapness of construction.

With this object in view the invention consists in certain novel and peculiar features of construction and combinations of parts, as will be hereinafter described and claimed, and in order that it may be understood reference is to be had to the accompanying drawings, in which—

Figure 1 represents a top plan view of a part of a car-roof embodying my preferred form of construction. Fig. 2 is a side or edge view of the same. Fig. 3 is a transverse section taken on the line III III of Fig. 1. Fig. 4 is a sectional perspective view of a pair of supercarline-crestings, forming part of my invention. Fig. 5 is a perspective view of a slightly-modified form of the supercarline-crestings. Fig. 6 is a perspective view of a modification which embraces changes in the roof-plate construction as well as in the supercarline-crestings used in connection therewith. Fig. 7 is a perspective view of a modified form of roof-plate. Fig. 8 is a transverse section of the upper part of the roof, with roof-plates of the type shown in Fig. 7. Fig. 9 is a sectional view taken longitudinally of the car, but transversely of the supercarlines and roof-plates thereof, said figure illustrating still further modified form of roof-plate, whereby crestings for the supercarlines may be dispensed with. Fig. 10 is a similar view showing a modified form of supercarlines, roof-plates, and crestings.

Referring now to the drawings in detail, 1 designates the upper longitudinal sills of a car of the usual or any approved construction, and 2 the carlines of the same.

3 and 4 designate longitudinal strips secured upon the carlines of the car.

The construction thus far is common and forms no part of my present invention, except in combination with features which I will now proceed to describe.

5 designates the supercarlines, which are secured upon the strips 3 and 4 and the sills 1 and are provided in their side edges with semicircular grooves 6.

7 designates the roof-plates, preferably of sheet metal, resting upon said strips and sills and fitting snugly between the supercarlines. These plates are provided at their outer ends with the vertically-pendent extensions 8, bent upward and outward at their lower ends to provide the cutters 9 to receive the water flowing down said plates and discharge it at either end externally of the car.

10 designates the usual side bars, which are secured to the sills 1 and clamp the extensions 8 reliably in position and also provide a bearing for the outer ends of the supercarlines.

The roof-plates at their upper ends in my preferred form of construction are coiled or convoluted, as shown at 11, and enveloping said coils or convolutions is a ridge-cresting 12, the sides of said cresting being coiled up within the coils or convolutions 11 of the roof-plates in order to provide for a relatively pivotal movement of said parts in a vertical plane, this pivotal connection serving to accommodate any expansive or retractive movement of the car structure due to heat, cold, forcible contact with other objects, or from any other cause. This pivotal connection serves to reliably interlock the plates with the ridge-cresting, and thereby prevent independent longitudinal movement (transverse of the car) of the roof-plates and incidentally prevents any water getting beneath said plates, and consequently entering the car at this point. The roof-plates are, furthermore, provided with coils or convolutions 14, fitting snugly in the semicircular grooves 6 of the supercarlines, this connection serving as an

additional means to prevent any independent upward movement of the roof-plates.

15 designates the supercarline-crestings. These crestings are of length to extend from one edge of the roof to about the opposite side of the ridge-crestings 12, one set of crestings 15 overlapping the upper or inner ends of the companion or opposing set, as shown most clearly in Figs. 3, 4, and 5. These supercarline-crestings, like the roof-plates and ridge-crestings, are by preference of sheet metal and stamped or otherwise provided at their side margins with the depending inwardly-turned coils or convolutions 16, these coils or convolutions fitting snugly in the coils or convolutions of the roof-plates, and thereby interlocking the roof-plates and supercarline-crestings together and yet permitting a slight pivotal movement, if necessary, to accommodate a movement of the car structure.

The outer ends of the supercarline-crestings between the coils or convolutions thereof are turned upward to provide the shallow gutters 17 to collect the water flowing down the crestings and deflect it to one side or the other upon the roof-plates, and thereby preserve the woodwork of the car as far as possible from contact with the water. The coils or convolutions 16 of said crestings preferably terminate a little outward of the crestings 12, and the plate is stamped or bent from such point to form the outwardly-extending ribs or flanges 19, resting upon the roof-plates, and the angular extensions 18, the extensions 18 of one set of crestings 15 overlapping the extensions 18 of the opposing set of crestings 15, as shown clearly in the drawings, the vertical portions or arms of said angular extensions fitting against opposite sides of the crestings 12, so as to embrace the same snugly, as shown in Fig. 3. By this arrangement it is apparent that access of water to the supercarlines at points between adjacent or contiguous roof-plates is reliably prevented and that provision for expansion or contraction of the roof is at the same time provided for, as the crestings may slide to a limited extent longitudinally from or toward each other, all the while enveloping the contiguous ends of the ridge-crestings. The ribs or flanges 19 also serve to stiffen and strengthen the angular extensions of their respective crestings.

In the preferred form of construction the only provision for preventing the carline-crestings from rising up from the supercarlines is their interlocked connections with the side coils or convolutions of the roof-plates and the fact that they overlap each other at their inner ends. In the modified form of construction shown in Fig. 5 an additional provision against upward movement of said crestings is made by interlocking the companion supercarline-crestings together. To accomplish this, one of the supercarline-crestings at its upper or inner end is bent back upon itself, as shown at 20, and the overlap-

ping end of the supercarline-cresting terminates in a hook 21, which underlaps the bent-back portion 20, this connection serving not only to prevent independent upward movement, but also serving to limit longitudinal movement away from each other, as will be readily understood. Furthermore, to serve as additional means for preventing independent lateral movement the bent-back portion 20 at its free end, preferably, is provided with a depending arm 22, while diagonally opposite the overlapping portion of the companion cresting is provided with an arm 23. The arm 22 bears against one end of the hook 21, while the arm 23 bears against the opposite side of the bent-back portion 20, and also of the integral portion immediately below. This form of cresting is used in connection with the roof-plates shown in Figs. 1 to 3, inclusive.

In the construction thus far described the ridge of the roof is flanked at each side by a coil or convolution of the roof-plates. In Fig. 6 this double coil or convolution construction is dispensed with and the coils or convolutions formed at the upper or inner ends of the roof-plates are interlocked together, as at 24, at the ridge-line or apex of the roof. With this arrangement of the roof-plates the same style of supercarline-crestings may be employed; but I prefer to dispense with the angular extensions 18 and in lieu thereof provide the upper or inner ends of the crestings 15 with coils or convolutions 25, these coils or convolutions being pivotally interlocked together and to the interlocked coils or convolutions 11 of the roof-plates. In other respects the construction of the parts is precisely the same.

In Fig. 8 the roof structure is provided with the usual ridge-pole 26, provided with longitudinal grooves 27 in its under side edges. In this connection I by preference provide the roof-plates with the side coils or convolutions 14 for engagement, as described, with the semi-circular grooves 6 of the supercarlines, (see Fig. 2,) and in addition and in lieu of the coils or convolutions 11 at their upper ends with the extensions 28, formed with marginal upturned beads 29, said beaded extensions 28 projecting into the grooves 27 of the ridge-pole. (See Fig. 8.) With this construction the ridge-crestings may be dispensed with. Either style of supercarline-cresting shown in Figs. 4 or 5 may be employed in connection with this type of roof-plate.

In Fig. 9 is illustrated a still further modified form of roof-plate 7. In this connection the coils or convolutions 14^a at the sides of the roof-plates are of semicircular form in cross-section and terminate in vertical flanges 30, projecting upward and engaging grooves 31 in the supercarlines. This style of roof-plate may be used with the supercarline-crestings, if desired, may terminate in ridge-coils 11, if desired, to be enveloped in the ridge-crestings, or may terminate in a beaded extension, as shown in Figs. 7 and 8, and engage grooves

in opposite edges of the ridge-pole. If no ridge-pole is employed, they will by preference be formed with ridge-coils at their upper ends.

In Fig. 10 a truncated supercarline is shown, 5 so as to leave the grooves 6^a, corresponding to grooves 6 in its side edges, in quadrant instead of semicircular form. With this style of supercarline a supercarline-cresting 15^a is employed, this cresting being formed at its 10 opposite side margins with the coils or convolutions 16^a, corresponding to coils or convolutions 16. As these coils or convolutions 16^a are oppositely disposed to the coils or convolutions 16, it is necessary that the engaging 15 coils or convolutions 14^a of the roof-plates 7 be also coiled in the opposite direction, that they may pivotally interlock with the coils or convolutions 16^a. With this style of construction the same conditions obtain as with 20 the preceding figure—that is to say, the roof-plates may terminate in ridge-coils to be enveloped by ridge-crestings or may be provided with beaded extensions to engage grooves in the side edges of the ridge-pole.

25 From the above description it will be apparent that I have produced a car-roof which embodies the features of advantage enumerated in the statement of invention and which is susceptible of various changes in the detail 30 construction, form, arrangement, or proportions of the parts without departing from the spirit and scope or sacrificing any of the advantages of the invention.

Having thus described the invention, what 35 I claim as new, and desire to secure by Letters Patent, is—

40 1. In a car-roof, supercarlines provided with segmental grooves in their side edges, roof-plates terminating in side coils or convolutions fitting in said grooves, and at their upper ends in coils or convolutions, and ridge-crestings enveloping and pivotally interlocked with said upper coils or convolutions of the roof-plates, substantially as described.

45 2. In a car-roof, supercarlines provided with segmental grooves in their side edges, roof-plates terminating in side coils or convolutions fitting in said grooves, and at their upper ends in coils or convolutions, ridge-50 crestings enveloping and pivotally interlocked with said upper coils or convolutions of the roof-plates, and supercarline-crestings provided with side coils or convolutions having an interlocked relation with the side coils or convolutions of the roof-plates, and overlapping the said ridge-crestings, substantially 55 as described.

55 3. In a car-roof, supercarlines provided with segmental grooves in their side edges,

60 roof-plates terminating in side coils or convolutions fitting in said grooves, and at their upper ends in coils or convolutions, and at their lower ends in gutters, ridge-crestings enveloping and pivotally interlocked with said upper coils or convolutions of the roof-65 plates and supercarline-crestings provided with side coils or convolutions having an interlocked relation with the side coils or convolutions of the roof-plates, overlapping said ridge-crestings, and provided at their outer 70 or lower ends with gutters to discharge water down on the roof-plates, substantially as described.

4. In a car-roof, supercarlines provided with segmental grooves in their side edges, 75 roof-plates terminating in side coils or convolutions fitting in said grooves and at their upper ends in coils or convolutions, and with depending extensions terminating in gutters, and clamped in position, ridge-crestings enveloping and pivotally interlocked with said upper coils or convolutions of the roof-plates, and supercarline-crestings provided with side coils or convolutions having an interlocked relation with the side coils or convolutions 85 of the roof-plates, overlapping said ridge-crestings, and provided at their outer or lower ends with gutters to discharge water down on the roof-plates, substantially as described.

5. In a car-roof, supercarlines, roof-plates 90 fitting between the same and provided with side coils or convolutions and with coils or convolutions at their upper ends; said coils or convolutions being pivotally secured to permit of a limited vertical movement at the 95 outer ends of said plates, and supercarline-crestings interlocked at their side margins with the side coils or convolutions of the roof-plates, substantially as described.

6. In a car-roof, supercarlines provided 100 with grooves in their side edges, roof-plates between said supercarlines provided with side coils or convolutions fitting in said grooves and with ridge coils or convolutions, ridge-105 crestings, pivotally connecting and interlocked with said last-named coils or convolutions of the roof-plates, and supercarline-crestings pivotally interlocked with the side coils or convolutions of the roof-plates and provided with extensions enveloping the contiguous ends of said ridge-crestings, substantially 110 as described.

In testimony whereof I affix my signature in the presence of two witnesses.

DANIEL WATSON.
